UNITED STATES PATENT OFFICE

ALFONS J. SZUMKOWSKI, OF CHICAGO, ILLINOIS

SWIMMING DEVICE

Application filed May 9, 1932. Serial No. 610,108.

My invention relates to improvements in swimming devices in which the primary object is to provide a swimming garment or harness to be worn upon one's body, with a novel arrangement of inflatable air chambers and air tubes connecting them, mounted upon strips of canvas or some other strong material sewed crosswise and the air chambers to be in sufficient numbers and size to float or support a person in water. The air chambers consist of groups of individual air tubes placed side by side and parallel to the body and tapering down to small air passages where the bends of the body occur while in action.

My second object is to provide a swimming device having the highest degree of safety, the air chambers of which are arranged in groups or sections about the wearer's body, the sections being separated or isolated from each other by hand operated and specially designed shut-off valves placed between these sections to prevent deflation of the entire device in case of a rupture in any one of the sections and this novel feature of my invention gives the wearer full confidence in its safety and reliability.

My third object is to provide a swimming device with maximum efficiency introducing the new and novel method of attaching permanently to one end of the main air passage a hand operated air bulb whereby any amount of air may be injected into the air chambers, thus imparting to the device the maximum capacity of air and therefore maximum efficiency. This obviously does away with the unsatisfactory old process of blowing up the inflatable device by one's mouth and breath.

My fourth object of the invention is to provide a swimming device the construction of which is simple, its combination logical, its price reasonable, efficient and safe in use for the beginner in swimming as well as for the experienced one for long distance swimming, also comfortable to wear and pleasing in appearance, and finally which can be folded into a compact bundle when not in use.

I attain these objects by the device illus-

trated in the accompanying drawing, in which—

Figure 1 shows the device when taken off the body and stretched out upon a table and showing only the skeleton or the continuous air tubes and air chambers with shut-off valves between sections and the automatic air bulb or pump at one end of the main tube and the deflating valve at the other end.

Figure 2 shows front view of the device applied on the body of a person.

Figure 3 shows back view of the device applied on the body of a person.

Figure 4 shows construction and cross section of the shut-off valves.

No drawing of the air bulb is shown here as this is commonly used on atomizers and its construction, shape and size are well understood.

Proceeding with the detailed description of the drawing I use similar numerals to refer to similar parts throughout the several views.

In Figures 1, 2 and 3 number 1 indicates tubular air chambers, similar to short lengths of bicycle inner tubes, tapering down to small air passages 2 connected to the main air tube 3 and forming a continuous air passage therewith. The main supply air tube 3 generally encircles the wearer's waist the same as an ordinary belt would but instead of a buckle at one end I attach to it permanently the mechanical air bulb or pump 4 and closed with the screw cap 5; at the other end of the main tube I place the deflating valve 6 and closed with the screw cap 7. Numbers 8 and 9 are air passages connected with each other and the main air pipe 3 to make a continuous air passage to air chambers 1 projected down to the upper parts of the wearer's legs and partly encircling them to help float the heavy or mid-portion of the human body in the water. Number 10 represents the hand operated shut-off valves placed in the main air passage 3, showing their relative position with the groups or sections of air chambers and closing-in the air or isolating each section from the other and preventing escape of air from the entire

device in case of a blow out or rupture of either of the sections.

The above described device, preferably made of rubber or some material impervious to water, is placed upon a base or strips 11 consisting of canvas or some other strong material sewed crosswise to lie upon and about the wearer's body in the manner shown in Figures 2 and 3. Number 12 shows buckles or some suitable clasps to fasten the ends of strips together on the wearer's chest, waist and legs so that the whole swimming garment may be put on and taken off as any other garment. Number 13 represents bathing trunks or bathing suit over which the swimming garment or harness may be worn.

As illustrated in Fig. 4 of the drawing the construction of the valve 10 is shown in more detail. In this figure there is shown a solid piece of cylindrical rubber 15 which is rigidly mounted within the main air tube 3 and made a part thereof. At one end of the body 15 is provided a passage 16, which passage communicates through the downwardly extending passage 17 with the passage 18 which is in communication with the main air tube 3 on the other side of the body 15. A suitable valve seat 19 is formed in the passage 17. There is also provided a cut-out portion 20 at the lower portion of the body 15 within which cut-out portion is mounted a membrane 21 of any suitable material, such as thin rubber or the like, said membrane being provided intermediate its ends with a solid tip 22 which forms a valve and is disposed in position to be moved to seat upon the valve seat 19. A screw 23 is threaded through a bearing 24 formed in the sleeve 25 which surrounds the body 15, the tip of the screw 23 being disposed against the tip 22 to urge the latter to its seating position. A knurled head 26 is provided for the screw 23 to facilitate the turning of the same. The provision of the membrane 21 will insure against the escape of air through the threaded sleeve 24 and its associated screw 23.

Taking up this device in detail and as applied in practice I take strips of some strong material such as canvas, the width and number of the strips depending upon the size and number of tubular air chambers used, and sew them crosswise to form a garment or harness to be worn upon one's body, arm-holes being formed by the strips giving this swimming device the general appearance of a man's vest. The strips going about the neck, chest, waist and upper parts of the legs should be as few as possible and only enough of them to hold the device snugly upon the wearer's body and to form a base for the strips carrying the air chambers which lie parallel to the body and to each other. The strips encircling the body in the manner described above are just so many belts open in front and provided with either buckles or

clasps to fasten them together to hold the swimming garment upon the wearer's body as snugly as desired. The network of these strips lie upon the chest and back of the swimmer. In the front the strips are extended down below the waist line on either side of the stomach in order to prevent the air chambers from protruding on the stomach and down to the upper parts of the wearer's legs where another network of strips appear but in smaller proportion. Two strips are placed in the back from the waist down to engage those strips encircling the legs in order to hold the harness from crawling up the body while in the water as shown in Figure 3. No air chambers or strips parallel to the body are placed at the sides of the wearer or inner portions of the legs so that the swimmer has a perfect freedom of movement of the arms and limbs. To allow for small variations in the sizes of the wearers, pleats may be introduced in the strips at intervals and sewed down to be ripped and let out wherever necessary, as this action will not interfere with the air containing parts of the device. Where there is an extreme difference in sizes and body peculiarities of the wearers a different size of this device must be made for them.

Proceeding now with the inflatable part of my invention as described in Figure 1 I place it upon the network of strips just described and attach to it by covering the inflatable parts with strong strips of light cloth and sewed down edge to edge with the said base strips, thus forming the inner and outer tubes, the outer tube of cloth prevents a blow out or rupture to the inner tube due to excess of air or weakness of the inflatable parts of the device. If rubberized cloth is used for inflatable portions of the device then projections of cloth may be left out the full length of air chambers and both sides thus may be attached to base strips which give the same effect and protection to air chambers as above.

Now, the swimming garment is put on the wearer's body over a bathing suit or trunks and strips encircling the body and legs fastened by means of buckles or clasps. At this stage the deflating valve 6 is closed by its screw cap 7 and the shut-off valves between sections and the bulb cap 5 opened. This valve 6 may be used to partially fill the air parts by use of one's mouth then completing inflation by the air bulb; this valve may also be used to drain the device of any water accumulated in the air chambers due to rupture. The air is forced into the chambers by squeezing the air bulb a few times by hand and closing it with the bulb cap 5 to prevent water forcing itself into the air chambers, and this bulb may be compressed neatly under a belt or some suitable clasp to prevent it from dangling about the waist. The shut-

off valves 10 are now closed by hand by turning the heads of screws or plungers. The wearer is now ready to go into the water with full confidence in the safety and reliability 5 of this swimming device whether he is only a beginner in swimming or experienced one desiring to use it for long distance swimming.

It is obvious, should one of the sections be ruptured the buoyancy of the remaining sections will be sufficient to allow the swimmer to reach safety. It is also apparent that efficiency of this device is still further enhanced by designing individual air chambers as any 10 one of them on becoming ruptured may be eliminated temporarily by tying up where the rupture occurred thus leaving the balance of the sections intact and the entire device losing only a small fraction of its buoyancy. The sections are so arranged that should rupture occur in one section there is no danger of the swimmer being tipped over on his head by being unbalanced as each section is extended along parallel lines to the 15 body and is deflated its full length so that the swimmer's body may be tipped to one side but never toward his head or feet. The amount of tubular air chambers on the front of the device is balanced by the size and number 20 of tubular air chambers on the back of the garment.

It is advantageous to make this device in the form of a harness composed of strips instead of making it into one composite bathing and swimming suit, because the former 25 may be put on and taken off immediately when out of the water without resorting to privacy and the swimmer may remain on the beach for other sports and pleasures.

40 I claim:

1. In an apparatus of the character described, a plurality of longitudinally disposed air containers arranged in groups and adapted to lie when worn on the body of a 45 person on the back and chest of the wearer, a belt adapted for disposition around the waist of the wearer, said belt forming a main air passage and being in communication with each of said groups of air containers, means 50 provided within said main air passage for establishing or cutting out communication between said main air passage and any one of said groups of air containers, one end of said belt terminating in a mechanical air 55 bulb by means of which the said air containers may be inflated and the other end of said belt being open and being adapted for closure by a suitable cap, whereby said latter end may be used as a mouthpiece for 60 partially inflating said air containers.

2. In an apparatus of the character described, a tubular water-proof belt adapted for disposition around the waist of a person, one end of said belt being provided with a mechanical air bulb by means of which air may 65

be introduced into said belt, a plurality of longitudinally disposed tubular members extending upwardly from said belt and arranged in groups, said groups being adapted for disposition against the chest and back of the wearer when the device is in position on a person, and a plurality of longitudinally disposed tubular members extending downwardly from the belt and arranged in two groups, each group being adapted for disposition on either side of the stomach of the wearer and extending downwardly along the wearer's legs to a point above the knees, means for securing the free-ends of said tubular members to each other and to the wearer, 70 valve means interposed within said tubular belt whereby the same may be actuated to either break or establish communication between any one of said groups of said tubular members and said tubular belt, and means 75 provided in said downwardly extending tubular members intermediate their ends to permit bending of said members so as not to interfere with the wearer in his usual swimming operations. 80

3. In an apparatus of the character described, a tubular air chamber adapted for disposition around the waist of a person, a plurality of tubular members extending upwardly from said tubular air chamber and being in direct communication therewith, said tubular members being arranged in groups spaced from each other, there being interposed a valve in said tubular air chamber between each of said groups, whereby communication may be established or broken 90 between any one group and the remaining groups by the actuation of said valve, said groups of tubular members being arranged 95 so as to lie against the back and chest of the wearer only, and a plurality of additional tubular members extending downwardly from said central air chamber and being disposed for disposition against the sides of the stomach of the wearer, the lower ends of said 100 last tubular members extending downwardly to a point approximately half way down to the knee of the wearer, said downwardly extending tubular members being provided intermediate their ends with restricted portions 105 to permit bending of the same at those points whereby the wearing of the device will not interfere with the usual swimming operations 110 of the wearer. 115

4. In an apparatus of the character described, a central air chamber adapted for disposition around the waist of a person, said central air chamber terminating at one end in a mechanical air bulb by means of which air may be supplied thereto, the other end 120 of said chamber being open and being provided with a suitable detachable cap for closing the same, a plurality of longitudinally disposed tubular members extending upwardly from said central air chamber and 125

being in direct communication therewith, said tubular members being arranged in groups and so disposed as to lie, when in position on the body of a person, against the chest and back of said person, transversely arranged straps spaced from each other connected to said tubular members, said straps being adapted for detachably securing the apparatus in place on the wearer, a plurality 10 of valves provided in said central air chamber for establishing and breaking communication between any one group of said tubular members and the remaining groups, said valves being interposed between each of said 15 groups, a plurality of downwardly extending tubular members in communication with said central air chamber, said last mentioned tubular members being arranged so as to lie against the side of the stomach of the wearer 20 and to extend downwardly substantially half way to the knee of the wearer, and straps connecting the lowermost ends of said downwardly extending tubular members, said straps being adapted for disposition around 25 the leg of the wearer for holding said downwardly extending tubular members in an extended position.

5. In a device of the character described, a transversely disposed central air chamber 30 adapted for disposition around the waist of a person, one end of said chamber being provided with an air bulb and the other end be-

ing provided with a deflating valve, a plurality of longitudinally disposed tubes extending upwardly from said central air chamber, each of said tubes being in communication with said chamber, said tubes 70 being arranged in groups spaced from each other, the spacing between said groups being such that when in operative position on the body of the wearer said tubes will lie against the chest and back of the wearer only, 75 a valve interposed in said central chamber between each of said groups of tubes, said valve being adapted for establishing and breaking communication between any one group of tubes and the remainder of the device, a plurality of downwardly extending tubes in communication with said central air chamber, said latter tubes being arranged in groups and disposed when the device is in operative position on the sides of the stomach 80 of the wearer and extending downwardly to a point substantially half way to the knee of the wearer, said last mentioned tubes being provided with restricted portions intermediate 85 their ends to permit bending of said tubes at those points, and means including transversely arranged straps to which said tubes are connected and by means of which the device may be securely and detachably fastened on the body of the wearer. 90
